UNITED STATES PATENT OFFICE.

JOHN H. C. ALEXANDER, OF BERKELEY, CALIFORNIA, ASSIGNOR TO ALEXANDER FAN & PROPELLER COMPANY, A CORPORATION OF CALIFORNIA.

PROPELLER.

1,003,958.

Specification of Letters Patent. Patented Sept. 19, 1911.

Application filed August 30, 1906. Serial No. 332,716.

To all whom it may concern:

Be it known that I, JOHN H. C. ALEXANDER, a subject of Great Britain, residing at Berkeley, in the county of Alameda and 5 State of California, have invented a new and useful Propeller, of which the following is a specification.

This invention relates to a propeller or fan of the class of devices which perform 10 their functions by rotational movement against the fluid in which they are immersed.

The object of this invention is to provide 15 a device of the character named, of simple and cheap construction and more efficient to perform a certain character of functions than the devices of this class heretofore. Fans and propellers having radial blades formed on the lines of helices or modifications thereof as heretofore constructed have 20 one peculiarity in common:—the fluid impelled from their working surface takes a rapidly diverging conical form. Attempts have been made to overcome this defect by the employment of circumferential casings, 25 ribs, flanges and the like. These, however, in many instances are undesirable and relatively costly additions, not economical of motive power. It is desirable in many instances to produce by means of a fan or propeller 30 a current of fluid substantially cylindrical in form under conditions in which it is impractical or otherwise undesirable to employ special devices, such as those heretofore referred to, for changing the form of the fluid 35 current created by the rotation of the fan. Conversely a fan blade, which creates when rotated, a conical form of current, is not economical when used as a motor deriving its power from a fluid current, as for 40 example, a windmill, and consequently undesirable.

Another object therefore, of the present invention is to provide a fan or propeller which will overcome the stated difficulties 45 by creating, when rotated, a substantially cylindrical current and further to accomplish this object without the aid of special deflectors. I accomplish this object by means of the devices illustrated in the accompanying drawings in which:

Figure 1. is an elevation of one half of a two-bladed propeller. Fig. 2. is a diagram showing the construction of the propeller blade and placed relatively to Fig. 1. in the 55 position of the absent half of Fig. 1. Fig. 3.

is a detail showing a rib-member. Fig. 4. is a plan of Fig. 1. Fig. 5. is a plan of one half of a propeller or fan formed of members, such as shown in Fig. 3. Fig. 6. is a plan of Fig. 3.

Reference is to be had to the drawings and especially to Figs. 2, 3, 5, to which the description hereinafter particularly refers, from which a clear understanding will be had, which will enable those skilled in the art, to produce fans or propellers in accordance with my invention for the various applications for which such devices are commonly used.

The form of construction shown in the figures mentioned, is selected to illustrate this disclosure, for the reason that besides being peculiarly adapted to bring out clearly the underlying principle, it has the additional practical advantage of being readily taken 70 apart and packed in small compass for transportation.

Fig. 3. is a view of a unit or rib-member, consisting of a boss or hub 1, adapted to fit on a shaft and provided with an arm or 80 projection 2, extending radially therefrom. At a suitable distance from the hub, the arm 2 is bent or deflected, so that the remaining portion of its length 3 forms a tangent to a circle larger than the hub. This is clearly 85 illustrated in Fig. 3. by the dotted continuation of arm 3 and the dotted arc struck from the center of hub 1.

I have applied to certain lines in the diagram Fig. 2, reference characters similar 90 to those designating corresponding parts of the construction in Figs. 4, 5, and 6.

Referring now to Fig. 5. it will be seen that a number of rod units, such as shown in Fig. 3. are arranged on a shaft 4, their hubs 95 touching each other, so that the planes of rotation of the members are parallel to and equi-distant from each other.

With reference to a plane at right angles to the plane of rotation of one of the members, the remaining members, of which the drawings show seven, are arranged successively at regularly varying distances from each other. This is clearly shown in Fig. 2. in which the angular spaces between the 100 members are arranged in the varying proportion which corresponds to the numerical sequence 3 4 5 6 7 8 9. This is clearly indicated by the finer lines in the diagram. The eight members thus arranged and se- 105 110

cured upon the shaft 4 form a frame or backing and also, so far as concerns the tangential parts 3 a form or mold to which the web of the vane may be attached and caused 5 to conform. The vane is shown in Fig. 5. at 5, and also in Fig. 2. as the space bounded by the inner and outer arc lines and the lower and the uppermost tangential lines 10 3, 3. This web may be made of any suitable material such as sheet metal, canvas, or any other material conformable to the rods 3. The web may be attached to the supporting rods in any of the ordinary ways, appropriate to the character of the web material 15 used.

The described construction, as illustrated in Figs. 2, 3, 5, 6, is appropriate for windmills, fans, and the like where lightness and portability are desirable features. For heavier 20 and stronger devices in which the knock-down feature is of minor, or of no importance, the device, as shown in Figs. 1 and 4, may be formed of cast metal as is customary with propellers. In this latter case 25 however the built up construction which has been described will be found a simple and convenient foundation for or means of producing a pattern from which the propeller,

in accordance with my invention, can be cast.

It is obvious from the description, that the angular spacing of the members, are not necessarily variable only, in the numerical sequence herein shown, but may be varied 30 in any other desired ratio, or even spaced 35 uniformly.

From the description and drawings it will be seen that the operating surface is in the nature of a helix or modified helix developed by a tangent to a circle concentric 40 to the hub, traveling around said circle in a helical or modified helical path.

Having thus described my invention, what I claim is:—

A fan or propeller blade having its entire 45 working surface generated by a line tangent to a cylindrical surface concentric with the axis, and parallel to a plane perpendicular to the axis, the line in sweeping the surface of the blade moving so that its point of 50 tangency to the cylindrical surface describes approximately a helix of variable pitch.

JOHN H. C. ALEXANDER.
